UNITED STATES PATENT OFFICE.

JOHN A. DE VITO, OF BOSTON, MASSACHUSETTS.

NON-REFILLABLE BOTTLE.

SPECIFICATION forming part of Letters Patent No. 716,391, dated December 23, 1902.

Application filed October 27, 1902. Serial No. 128,867. (No model.)

To all whom it may concern:

Be it known that I, JOHN A. DE VITO, a citizen of the United States, and a resident of Boston, in the county of Suffolk and State of 5 Massachusetts, have invented certain new and useful Improvements in Non-Refillable Bottles, of which the following is a specification.

This invention relates to improvements in 10 non-refillable bottles; and it has for its object to provide a simple and cheap construction of device which shall serve as a means for preventing the refilling of a bottle after the contents thereof have been removed, as will hereinafter be more fully shown and described, 15 reference being had to the accompanying drawings, wherein—

Figure 1 is a central longitudinal section of my non-refillable bottle, showing the diaphragm in its normal closed position within 20 the bottle-neck. Fig. 2 is a similar longitudinal section showing the bottle tipped during the discharge of its contents and the diaphragm released from its seat during such 25 operation, and Fig. 3 represents a detail top plan view of the diaphragm and the coiled spring to which it is yieldingly attached.

Similar letters refer to similar parts wherever they occur on the different parts of the 30 drawings.

In the drawings, A represents the body portion of a glass bottle, as usual, and B is the neck of the same. Within the lower portion of the neck is made an annular groove or recess C, adapted to receive and retain a coiled-wire spring D, the inner or central portion of which is attached in a suitable manner to a valve or diaphragm E, which may be made of metal, glass, or other suitable material, 35 as shown. Normally the said disk E rests upon the coiled spring D. Below the groove C is made an inwardly-projecting annular shoulder F, which serves to prevent the disk E from being forced downward into the bottom, and thus preventing the fraudulent refilling of the latter.

The disk E fits loosely within the lower

portion B' of the bottle-neck, and above such valve-containing part B' is made an enlargement B'', as shown in Figs. 1 and 2. 50

In using the device the bottle is first filled with the liquid, after which the valve-disk E and its connected coiled spring D are pushed downward through the bottle-neck until the outer portion of said spring is retained in the 55 annular recess C, as shown in Fig. 1, and in such position the disk E is held centrally and yieldingly upon the spring D, as shown in said Fig. 1.

To empty the bottle, it may be tipped or inclined as shown in Fig. 2, when the gravity and force of the outflowing liquid will cause the disk E to yield, with the spring D, toward the mouth of the neck sufficiently to allow the liquid to flow out freely between the periphery of said valve-disk and the interior of the enlarged neck portion B'', as shown in Fig. 2. As soon as the bottle is placed in its vertical normal position the valve E will automatically assume the normal closed position 70 shown in Fig. 1, which closing movement is effected by the coiled spring D, that is connected to said disk E. 65

The valve E, supported on the coiled spring D, effectually prevents the refilling of the 75 bottle after once emptied.

What I wish to secure by Letters Patent and claim is—

The herein-described non-refillable bottle, consisting in combination, a bottle A, having 80 a neck B, a neck enlargement B'', a valve-disk E, and a coiled spring D, yieldingly connected to said disk, a neck-recess C, for receiving and retaining said spring in position, and a valve-arresting shoulder F arranged 85 below said spring substantially as and for the purpose set forth.

In testimony whereof I have affixed my signature in presence of two witnesses.

JOHN A. DE VITO.
